UNIT FOR DRAINAGE SYSTEMS

Maurice R. Gutman, Lynbrook, N. Y.

Application November 10, 1942, Serial No. 465,177

6 Claims. (Cl. 61—10)

My invention relates to units for drainage systems, including systems for the disposal of the effluent water from septic tanks, grease traps etc., the invention being suitable also for use in draining water from swampy ground, after the manner of French drains.

In the draining of comparatively clear water from septic tanks and the like, it is frequently conducted through drain tile to porous soil or gravel beds, to effect dissipation of the effluent water into the soil. Usually the drain tile sections have their ends spaced slightly apart to allow the water to leak between such ends, into the absorption bed, but the pipes are embedded in the gravel or the porous soil, and there is infiltration of dirt between the ends of the tile sections, so that trouble is frequently encountered through clogging of the drain tile. Even where no such infiltration of dirt occurs, there is obstruction to free flow of water through these spaces between the ends of the pipes or tile sections, because of close proximity of the gravel or the like in which the drain tile is embedded. This objection applies also to the draining of soil or swampy land to remove water therefrom.

One object of my invention is to provide a structure of the character referred to, wherein the drain pipes are supported in such manner that they will not become clogged by dirt or gravel at the absorption beds, and wherein there is no obstruction to free flow of water from the pipes to the absorption beds.

Another object of my invention is to provide a system of the character referred to wherein the parts can be made largely from conventional forms of sewer pipe and the like.

Still another object of my invention is to provide a drainage system with an improved manner for introducing chemicals for treating the liquid passing therethrough, or for dissolving grease, which means may also serve as a convenient manner for effecting aeration, with supply of oxygen to the effluent from septic tanks or other source of sewage.

A further object is to provide a means and a method of laying conduits of drain tile or sewer pipes in such manner that danger of tree roots entering the conduit through holes or joint spaces is reduced.

Some of the forms which my invention may take are shown in the accompanying drawings wherein Figure 1 is a longitudinal sectional view through an absorption bed, with my invention incorporated therewith; Fig. 2 is an enlarged view taken on the line II—II of Fig. 1; Fig. 3

is a view taken on the line III—III of Fig. 2; Fig. 4 shows a modification of the structure of Fig. 2; Fig. 5 shows a further modification of the structure of Fig. 2; Fig. 6 is a modified view of one of the drain tile members of Fig. 1; Fig. 7 is a perspective view of a modification of the drain pipe and shield structure of Fig. 3; Fig. 8 is a side view of the drain pipe of Fig. 7; Fig. 9 shows another modification of the structure of Fig. 1; Fig. 10 shows still another form of the invention, in fragmentary plan view; Fig. 11 is an end view thereof partly in section, and Fig. 12 is a fragmentary perspective view showing three of the units of Fig. 10 in assembled relation.

Referring first to Figs. 1, 2 and 3, 11 indicates a sewer or drain line leading from a septic tank or some other source, slightly sloping downwardly in the direction indicated by the arrow. This drain line 11 is mounted in vertically-spaced relation to an absorption bed 12, which may be of gravel, broken stone, or simply a porous soil. Shield members 13 are placed upon the absorption bed 12 and may conveniently consist of ordinary sewer pipes split in half lengthwise thereof. Drain pipes 14 are supported within the shield members 13. To this end, the members 13 and 14, while in a plastic or green condition, can be pressed together and then fired, so that they will, in effect, be fused together at 15, thereby affording vertical support for the drain pipes 14. The pipes 14, while green, can have one-half of their hubs cut away, as indicated at 16, so that the pipes can have better fit and accurate alignment with one another. Also, they have slots or holes 17 punched therethrough, to permit water to flow from the pipes to the absorption bed.

At least one of the shields 13 has a hole cut therein, and a pipe 20 extending upwardly therefrom, the pipe 20 having communication through the shield, with the space above the filter bed, either directly or through one of the pipes 13. This pipe can serve as a means for introducing chemicals, grease solvents etc. to the filter bed, and when its cover 21 is removed, it can serve as a ventilating pipe or for aeration of the filter bed to admit oxygen of the atmosphere to the waste material in the bed.

It will be understood that in the case of the above-described structure, as well as certain of the other forms herein shown, the parts may be made of other materials such as concrete or metal. Also, unperforated drain pipes can be used,

since their ends can simply be spaced apart to provide lateral flow passageways.

In Fig. 4 I show an arrangement wherein the drain pipes 14 can be supported by plates 19 that may be of clay and fused to the shields 13 instead of the drain pipes being fused or burned to the shields 13. In this arrangement, the pipes 14 can be inserted and removed as desired, without the necessity of breaking them from the shields.

In Fig. 5, the pipes 14 are shown as supported on stools or chairs 18 at intervals, in vertically-spaced relation to the absorption bed 12.

As shown in Fig. 6, the pipes 14 may be perforated on only one side, in which case one pipe 15 will discharge laterally in one direction and the succeeding pipe laterally in the opposite direction, the holes 17 in the succeeding pipe being in the opposite side thereof.

Referring now to Figs. 7 and 8, I show a somewhat different form of shield and drain pipe arrangement that is suitable for mounting above an absorption bed. The shield 23 may be of metal or other suitable material, and is provided with flanges 24 that will afford it a firmer support on an absorption bed. The drain pipe 25 is similar to the drain pipes 14 and carries a metal strip or strips whose ends 26 and 27 are bent backwardly over the upper surface of the shield. Notches are provided in the ends of the shield to receive the tongues or clips 26-27, so that when a number of shields are used, they can be placed with their adjacent ends in abutting relation, to exclude dirt. Also, the successive shields can overlap one another at their ends somewhat, to more effectively exclude dirt. It will be understood that the pipe 25 could be bolted to the shield, or could be welded thereto—when they are made of metal.

In Fig. 9, I show an arrangement wherein a drain pipe 30 is provided with branches 31 and 32 for connection with perforated drain pipes 33 and 34 respectively, that extend through the upper portion of a box or shield 35 to be mounted upon a drainage bed and which is open at its bottom. The box 35 has partitions or walls 36, 37 and 38 that are recessed for the reception of the drain pipes, it being understood that a series of these boxes can be placed in end-to-end relation. The partitions and walls are perforated in their lower portions to facilitate distribution of water in the box, and a cover 39 is provided for the box, to exclude dirt.

Figs. 10, 11 and 12 show still another arrangement. In this structure inverted channel elements 41 are employed. These may suitably be formed of clay flue liners that are of rectangular form in cross section and split lengthwise while green, to form two channels from each flue liner. Also, they are recessed on their upper sides to receive drain pipes 43 that have perforations in their lower portions for the discharge of water to the absorption bed. In this instance, the pipes 43 themselves serve as a portion of the shield for excluding dirt from the spaces within the main shield elements 41. Perforations 42 are provided through the vertical sides of the members 41 to effect distribution of the water over the absorption bed.

While the invention has been described as used more particularly in the laying of drain tile, it can also be employed in connection with the laying of sewer lines. These lines will be laid in substantially the same manner as the drain pipes, but the pipe would be of conventional form—with

the hub connections complete and no lateral openings. While the joints of sewer pipes are usually cemented, this is not always done, and furthermore, cemented joints sometimes break, through settling or otherwise. If the sewer pipes are supported above the bottom of the sewer trench and shields placed to exclude dirt from the space below them, the tendrils of tree roots will not ordinarily come into contact with them.

I claim as my invention:

1. A unit for use in drainage systems, comprising a shield of approximately semi-tubular form adapted to be placed with its longitudinal edges upon an absorption bed, a drainage conductor supported in unitary relation with the upper inner surface of the shield and provided with lateral flow passages, the drainage conductor being of small vertical and horizontally-lateral dimensions relative to the shield, whereby it may be supported by the shield in completely vertically-spaced relation to an absorption bed and with its lateral flow passages spaced substantial distances from the sides of the shield.

2. A unit for use in drainage systems, comprising a shield of semi-tubular form adapted to be placed with its longitudinal edges on the surface of an absorption bed, and a drain pipe of small diameter relative to the width and depth of the shield, secured to the upper inner wall surface of the shield, the pipe having drain openings and being slightly off-set in a direction longitudinally of the shield so that one end projects slightly beyond one end of the shield and the other pipe end is inset slightly at the other end, whereby adjacent ends of the drain pipes are overlaid by the shields when a plurality of units are placed in end-to-end relation.

3. A unit for use in drainage systems, comprising a shield of semi-tubular form adapted to be placed with its longitudinal edges on the surface of an absorption bed, and a drain pipe of small diameter relative to the width and depth of the shield, secured to the upper inner wall surface of the shield and provided with perforations to afford flow of water laterally therefrom, the pipe being provided at one end with a hub-like portion in position to receive and align a drain pipe end of an adjacent unit.

4. A unit for use in drainage systems, comprising a shield of semi-tubular form adapted to be placed with its longitudinal edges on the surface of an absorption bed, a drainage conductor fused to the upper inner surface of the shield and having lateral flow passages, the drainage conductor being of small vertical and horizontally-lateral dimensions relative to the shield, whereby it may be supported by the shield in completely vertically spaced relation to an absorption bed and with its lateral flow passages spaced substantial distances from the sides of the shield, and means integral with the unit, for holding one end thereof in aligned relation with an end of an adjacent unit.

5. A drainage system comprising a plurality of units arranged in end-to-end relation, each unit having a shield of semi-tubular form adapted to be placed with its longitudinal edges on the surface of an absorption bed, a drainage conductor in each shield, of small diameter relative to the width and depth of the shield, means for securing the drainage conductors to the upper inner wall surfaces of their respective shields, and means on one of the units for maintaining the adjacent end of another unit in axial alignment therewith, lateral flow openings being pro-

vided from the drainage conductors at points spaced substantial distances above the absorption bed and from the sides of the shields.

6. A unit for drainage systems, comprising a shield member of generally channel form adapted to be placed with its edges upon an absorption bed, a drain conduit carried by the shield, within an upper portion of the shield and having its

lower-most wall area in vertically-spaced relation to the plane of the lower edges of the shield member, and means providing for discharge of liquid from the conduit into the shield member at points spaced substantial distances from the sides of the shield.

MAURICE R. GUTMAN.
